US0D1113814S

(12) **United States Design Patent** (10) **Patent No.:** **US D1,113,814 S**
(45) **Date of Patent:** **** Feb. 17, 2026**

(54) **BEHIND THE EAR HEADSET**

- (71) Applicant: **GN Audio A/S**, Ballerup (DK)
- (72) Inventors: **Kevin Batson**, Ballerup (DK); **Brian Collins**, Ballerup (DK); **Christopher J Frederick**, Ballerup (DK); **David Jaques**, Ballerup (DK); **Iain Scott Pottie**, Ballerup (DK); **Thomas F Terrien**, Ballerup (DK)
- (73) Assignee: **GN AUDIO A/S**, Ballerup (DK)

(**) Term: **15 Years**

(21) Appl. No.: **30/008,681**

(22) Filed: **Jun. 17, 2025**

(57) **CLAIM**

The ornamental design for behind the ear headset as shown and described.

DESCRIPTION

FIG. 1 is a top, front, right perspective view of a behind the ear headset showing the new design;

FIG. 2 is a bottom, rear, left perspective view thereof;

FIG. 3 is a front elevational view thereof;

FIG. 4 is a back elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the behind the ear headset that form no part of the claimed design.

1 Claim, 8 Drawing Sheets
